Primary Examiner — John M Otte

(57) **CLAIM**

The ornamental design for a display screen or portion thereof with a graphical user interface element, as shown and described.

DESCRIPTION

FIG. 1 is a front view of a display screen or portion thereof with a graphical user interface element showing a first embodiment of the design;

FIG. 2 is a front view of a display screen or portion thereof with a graphical user interface element showing a second embodiment of the design; and,

FIG. 3 is a front view of a display screen or portion thereof with a graphical user interface element showing a third embodiment of the design.

The dashed lines illustrate portions of the display screen or portion thereof with a graphical user interface element that form no part of the claimed design.

1 Claim, 1 Drawing Sheet
